UNITED STATES PATENT OFFICE.

WILLIAM FORSTNER, OF IRVINGTON, NEW JERSEY, ASSIGNOR TO FORSTNER CHAIN CORPORATION, OF IRVINGTON, NEW JERSEY, A CORPORATION OF NEW JERSEY.

CHAIN.

Application filed April 16, 1925. Serial No. 23,520.

This invention relates to an improved form of link for connecting together the loop-links of a chain section, and has for its object to provide a connecting link of this character which is formed initially in **S**-shape and is made of such a size, character and quality of stock as to tenaciously resist a straightening out or opening action after having been finally closed to link the 10 parts together, as to offer substantially the same strength, without having its joints soldered, as the other links of the chain which are either integral loops or those that have their joints soldered.

15 A further object of this invention is the cutting of the ends of the **S**-link so that these ends will closely fit against the opposite sides of its shank portion so as to reduce its opening at the joint to the minimum to render this unsoldered joint as nearly invisible as possible.

20 A still further object of this invention is the provision of a band, loop or member through which the shank portion of the **S**-link extends and which band extends through both of the eyes of the **S** when its ends are closed, the band being preferably of a width to cover or hide both of the end joints giving the **S**-link the appearance of 25 being formed of two separate loop-links connected by the band loops.

25 With these and other objects in view, the invention consists of certain novel features of construction, as will be more fully described, and particularly pointed out in the appended claims.

In the accompanying drawings:

30 Figure 1 is a side elevation of my improved form of chain showing the connecting link as having an ornamental link mounted thereon and showing the connector link as having an ornamental band mounted thereon.

Figure 2 is an enlarged elevation of the 35 connecting link.

Figure 3 is a perspective view of the ornamental band separated from the link.

Figure 4 shows the ornamental band as mounted on the **S**-shaped link, the ends of 40 this link being opened.

Figure 5 shows the ornamental band in section as mounted on the **S**-shaped link, the ends of which link are closed.

Figure 6 shows a side elevation of the ornamental band as mounted on the **S**-link 45

with the ends of the link closed, the band being of sufficient width to conceal or hide the joints of the link.

Figure 7 is a section on line 7—7 of Figure 5, showing the abutting ends of the link 50 as bearing closely against the wire of the shank portion thereof.

It is found in the practical construction of chains for personal wear, of advantage to form certain of its links or groups of 55 links so as to obtain a variety of ornamental effects by connecting up links of different shapes, colors and finish, and in order to readily connect up these different links or groups of links by a link which does not require its joints to be soldered, I have adopted a link substantially in the form of the letter **S** and of a wire whose stiffness and strength when closed into finished shape with unsoldered joints, is capable of resisting 60 an opening strain substantially equal to that of the other links of the chain which are of one piece or which have soldered joints, it being pointed out that a link of **S**-shape is capable of resisting approximately twice the 65 opening strain as the usual ring link, owing to the fact that the middle continuous integral shank portion thereof takes half the strain of both of its loops and this portion cannot yield. As it is found in some cases 70 of advantage to cover up or hide the unsoldered joints of this **S**-link, I have threaded the **S** through a band member and set the band in such a way that when the ends of the **S** are closed the band extends through 75 both of the loops or eyes formed thereby and being thus supported serve to effectually cover or hide both joints thereof thus causing the **S**-link to present the appearance of 80 two separate ring links connected by this 85 band member, the latter being capable of being formed of quite a different colored material, if desired lending variety to the 90 ornamental appearance of the chain; and the following is a detailed description of the 95 present embodiment of my invention showing one construction by which these advantageous results may be accomplished:—

With reference to the drawings, 10 designates the loop links of a chain, which may 105 be formed integral or with soldered joints, and 11 shows another form of link which connects the elongated link and which may also be provided with soldered joints and these groups or links 10 and 11 may be sub- 110

jected to the same treatment or coloring, if desired, and another desired ornamentation may be applied to the center of the loop link 10 of a color different from that of the link, if desired.

The essential feature of this invention is the provision of an S-shaped connecting link 12 which is preferably of a material which presents a resistance to spreading or opening which is as great or greater than that of the wire of the other links of the chain so that the ends 13 of this link may close or open the shank portion 14 thereof, and will resist without being soldered any of the usual strains to which a whole chain may be subjected.

In some instances, it is found of advantage to form a band loop 15 and to pass the shank 14 of the S-link through this band so that when the ends 13 of this link are closed upon the shank thereof this band will cover or hide these joints 16 of this link. Thus it will be seen that the S-shaped link takes on an entirely different appearance which is, instead of being of S-shape, it will appear like two separate ring links joined by a band 15. This band as it is not required to be attached by solder to the S-link may be previously treated independently of the S-link to take on a different color and lend a further variety of ornamental colors to the chain.

In other instances, I have found it of advantage to cut the ends of the wire of the S-link on an angle so that when closed they will lie parallel with the face of the shank to close the joint opening.

In still other cases, I have found it of advantage to even groove these end portions of

the wire so as to conform to the contour of 40 the shank of the S and so again reduce the joint opening to the minimum.

My improved construction of chain may be made very ornamental and by the use of the ornamental band on the S-shaped 45 link, the joints of this link are entirely concealed and the chain rendered much more attractive.

The foregoing description is directed solely towards the construction illustrated, but 50 I desire it to be understood that I reserve the privilege of resorting to all the mechanical changes to which the device is susceptible, the invention being defined and limited only by the terms of the appended claims. 55

I claim:

1. A chain structure comprising loop-links connected by an S-shaped link, the shank portion of the S-link being diagonally disposed to the longitudinal extension of the 60 chain, the end of each eye portion of the S-link abutting against its shank portion, and a band member extending through both of the eyes of said S-link to cover the abutting joints thereof. 65

2. A chain structure comprising loop-links connected by S-shaped links the shank portion of the S-link being diagonally disposed to the longitudinal extension of the chain, the end of each eye portion of the 70 S-link abutting against its shank portion, and a band member extending through both eyes of the S and of a width to cover the joint ends of the S, the shank portion of said S-link also extending through said band. 75

In testimony whereof I affix my signature

WILLIAM FORSTNER
